UNITED STATES PATENT OFFICE.

IDA M. ERICKSON, OF SEATTLE, WASHINGTON.

FASTENER.

1,402,405.

Specification of Letters Patent.

Patented Jan. 3, 1922.

Application filed September 13, 1919. Serial No. 323,520.

To all whom it may concern:

Be it known that I, IDA M. ERICKSON, a citizen of the United States of America, residing at Seattle, in the county of King and State of Washington, have invented certain new and useful Improvements in Fasteners, of which the following is a specification, reference being had therein to the accompanying drawings.

The invention relates to fasteners adapted especially for use upon wearing apparel. One object of the invention is to provide a fastener comprising hook and eye members which can be readily attached to wearing apparel by a person unaccustomed to doing the same and without complex tools. Another object is the provision of means for reinforcing the fabric of the wearing apparel, this means being further secured by the fasteners. A further object is the securing of the fastener in a way such that it will be concealed from view. Other objects of the invention reside in the novel arrangements and combinations of parts as more fully hereinafter set forth.

In the drawings:

Figure 1 is an inner side view of portions of wearing apparel secured to each other by means of the construction embodying my invention;

Figure 2 is an enlarged cross section on the lines 2—2 of Figure 1;

Figure 3 is a perspective view of the hook member;

Figure 4 is a side view of the eye member;

Figures 5 and 6 are, respectively, a side view and top plan view of a modified construction of hook member.

1 is the hook member formed of wire having the parallel prongs 2, the ends of which are rounded so that they can be readily inserted through the fabric of the wearing apparel, and the loop 3 which is of U-shape and is connected to the prongs 2 by means of the transversely extending portions 4. The loop 3 extends substantially parallel to the prongs 2, and the legs 5 of the loop have the portions 6 bent inwardly toward the prongs 2, so that when the hook member is in engagement with the eye member the inwardly bent portion 6 will retain the hook and eye members in engagement.

7 is the eye member which is also formed of wire. This eye member is U-shaped, and the ends of the prongs 8 are rounded so that

the same can be more readily inserted into the fabric of the wearing apparel.

For securing the eye member 7 to the wearing apparel, the edge of the latter, to which the eye member is secured, is hemmed, as at 9. The prongs 8 of the eye member are forced through the hem 9 of the fabric from its outer to its inner side and the ends 10 are bent over to secure the eye member thereto. For securing the hook member to the other edge of the fabric, which is also preferably hemmed, as at 11, the prongs 2 are inserted through the fabric forming the inner face of the hem 11, and the hook member is turned so that the transversely extending portions 4 engage this portion of the fabric, and the prongs 2 extend substantially parallel thereto for a distance, and are then bent transversely and extend through this fabric and have their ends 12 bent over to secure the hook member to the fabric. By means of this arrangement the fabric forming the outer face of the hem 11 conceals the hook and eye members from view.

For the purpose of facilitating the bending of the prongs of the hook and eye members at the proper points, the prongs have predeterminedly located weakened portions 13, which in the present instance are formed by notching the prongs.

To reinforce the fabric of the wearing apparel, reinforcing members 14 are provided which, as shown in Figures 1 and 2, comprise sheet metal plates formed of stampings and of suitable shape, these plates having apertures 15 through which the prongs of the hook and eye member extend and over which the end portions of the hook and eye members are bent. These plates distribute the pressure produced by the hook and eye member over a sufficient area of the fabric to prevent tearing of the latter.

As shown in Figures 5 and 6, the reinforcing member is formed of wire, which has its opposite ends 16 bent to form eyes, through which the prongs 17 of the hook member extend.

The ends of the prongs 17 are looped over to prevent disengagement of the reinforcing member. This form of reinforcing member may also be readily used with the eye member of the fastener.

The hook and eye members 1 and 7 respectively may be made in the factory in the forms shown in Figures 3 and 4, with the

shanks straight and weakened at predetermined points. The person, such as the home dress-maker, can easily apply the same to wearing apparel and also apply the fabric reinforcing members 14. Furthermore, the fastener can be easily removed when desired. Another important feature is that no sewing is required for securing the parts of the fastener.

10 What I claim as my invention is:

1. The combination with a fabric, of an attachable fastener member comprising a wire having a loop extending beyond one side of said fabric and having prongs extending through said fabric and bent over at their ends at predetermined points, and a single reinforcing member for said fabric between the opposite side of said fabric and the bent-over ends of the prongs, the latter holding said reinforcing member in place.

2. The combination with a fabric, of an attachable fastener member comprising a wire having a loop adjacent to one side of said fabric and prongs extending through said fabric and bent over at their ends, said prongs being weakened at predetermined points to facilitate bending of the same.

3. The combination with a fabric, of an attachable fastener member comprising a wire having a loop adjacent to one side of said fabric and prongs extending through said fabric and bent over at their ends, said prongs being weakened at predetermined

points to facilitate bending of the same, and a plate having apertures through which said prongs pass, said plate being secured by said bent over ends of the prongs.

4. The combination with a fabric having overlapping hems, of an attachable fastener for securing said hems to each other comprising cooperating hook and eye members, each having a loop at the adjacent sides of said fabric and prongs extending through said fabric and bent over at their ends and a single apertured plate on the inner side 45 of each of said hems and engaged by the prongs of each of said hook and eye members, the outer side of one of said hems concealing said hook and eye members.

5. The combination with a fabric having 50 a hem, of a hook member having a loop extending substantially parallel to and spaced from the inner side of said hem and having prongs extending through the fabric from the inner side of said hem extending substantially parallel thereto and bent inwardly to pass therethrough, the ends of said prongs being bent over, said prongs being weakened at predetermined points to facilitate bending of the same, and a reinforcing member for 60 the fabric secured thereto by the bent-over ends and having eyes through which said prongs extend.

In testimony whereof I affix my signature.

IDA M. ERICKSON.
